(57) **CLAIM**

The ornamental design for a battery charging station, as
shown and described.

DESCRIPTION

FIG. 1 is a front elevation view of a battery charging station,
showing my new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a right front perspective view thereof.
